CLAIM

The ornamental design for a strap for cord management, as shown and described.

DESCRIPTION

The present application relates to U.S. utility patent application Ser. No. 12/761,326, filed Apr. 15, 2010, to U.S. design patent application Ser. No. 29/368,746, filed Aug. 27, 2010, and U.S. design patent application Ser. No. 29/368,754, filed Aug. 27, 2010.

FIG. 1 is a perspective view of our new design of a strap for cord management.

FIG. 2 is a top view of FIG. 1.

FIG. 3 is a bottom view of FIG. 1.

FIG. 4 is a view of a first side of FIG. 1.

FIG. 5 is a view of a second side of FIG. 1.

FIG. 6 is a view of a third side of FIG. 1.

FIG. 7 is a view of a fourth side of FIG. 1.

FIG. 8 is a perspective view of FIG. 1 shown in an alternate configuration of use in an environment of use; and, FIG. 9 is another perspective view of FIG. 1 shown in another alternate configuration of use in an environment of use.

The broken lines represent an environment of use that forms no part of the claim.
